UNITED STATES PATENT OFFICE.

HOWARD R. WESLEY, OF DETROIT, MICHIGAN.

SANITARY REVOLVING BATH-BRUSH.

1,191,860.

Specification of Letters Patent. Patented July 18, 1916.

Application filed August 19, 1915. Serial No. 46,243.

To all whom it may concern:

Be it known that I, HOWARD R. WESLEY, a citizen of the United States, residing at Detroit, in the county of Wayne and State of Michigan, have invented certain new and useful Improvements in Sanitary Revolving Bath-Brushes, of which the following is a specification.

The present invention relates to certain new and useful improvements in bath brushes, and has for its object to provide a device of this character which embodies novel features of construction whereby the brush is continuously rotated and supplied with fresh water when in use.

Further objects of the invention are to provide a revolving bath brush which is simple and inexpensive in its construction, which is so constructed as to utilize the flow of water to the brush head for rotating the latter, which is self cleaning and will always remain in a sanitary condition, which can be conveniently handled and manipulated, and which is invigorating in its use.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a side elevation of a revolving bath brush constructed in accordance with the invention. Fig. 2 is a vertical longitudinal sectional view through the same. Fig. 3 is a plan view, the revolving brush plate being removed and portions being broken away and shown in section. Fig. 4 is a top plan view of the brush plate with the bristles removed, the paddle wheel being shown by dotted lines. Fig. 5 is a transverse sectional view through the handle.

Corresponding and like parts are referred to in the following description and indicated in all the views of the drawings by the same reference characters.

Specifically describing the present embodiment of the invention, the numeral 1 designates the handle which has an elongated formation and may be constructed of wood or other similar material. The exterior of the handle is shown as provided with a series of annular enlargements so that it can be firmly

grasped by the hand, while a water pipe 2 extends longitudinally through the handle, being arranged at one side of the axis of the handle. One end of the water pipe 2 projects beyond the free end of the handle and has a flexible water supply tube 3 slipped thereon, while the opposite end of the water pipe 2 is threaded in the end of a water passage 4 provided in the head 5 and entering the paddle wheel chamber 6 thereof on a tangent.

The head 5, as well as the other metal parts of the bath brush, is preferably constructed of some light material such as aluminum. A neck 5^a projects laterally from one side of the head 5 and terminates in a sleeve 5^b which is fitted over the end of the handle 1 and permanently connected thereto by suitable fastening members such as the screws 7. The body portion of the head has substantially the shape of a flat cylinder, being formed with a cylindrical chamber 6 which opens through the top of the head, the mouth of the chamber being rabbeted at 6^a, while a pivot post 8 projects centrally from the base thereof. The paddle wheel 9 is mounted to rotate within the cylindrical chamber 6, being formed with a cup shaped hub 9^a having a series of blades 9^b projecting radially therefrom. The cup shaped hub 9^a is open at the top thereof, and projecting upwardly from the center of the cup shaped hub is a bearing sleeve 10 which is adapted to receive the before mentioned pivot post 8 of the head 5. The blades 9^b are constructed to just clear the sides and bottom of the chamber 6 and to provide a series of water buckets between the same.

The bristles 11 are carried by and project from a circular plate 12 which is secured to the top of the paddle wheel 9 and serves to close the cylindrical chamber 6 of the head 5, the edges of the brush plate being received within the rabbeted mouth 6^a of the chamber 6. Suitable fastening members such as the screws 13 may be provided for securing the circular brush plate 12 to the edge of the cup shaped hub 9^a of the paddle wheel, and the center of the brush plate is formed with an opening for the reception of a retaining screw 14 which is threaded in the end of the pivot post 8 of the head 5. A washer 15 is preferably interposed between the head of the retaining screw 14 and the brush plate 12, and it will be seen that when this retaining screw is in position the brush

and paddle wheel are held against displacement, although they are free to rotate about the pivot post as a center.

The revolving brush plate 12 is provided with a number of radially extending series of water outlet openings 16 which communicate with the spaces or buckets between the adjacent blades 9^b of the paddle wheel. It will be observed that each series of openings 16 is located adjacent the front edge of that one of the blades 9^b which is at the rear end of the pocket or bucket as the paddle wheel rotates. It will also be observed that the blades 9^b of the paddle wheel are inclined and arranged at an angle to the brush plate 12, the edges of the blades remote from the brush plate being in advance of those edges of the blades adjacent the brush plate as the brush revolves.

It will thus be obvious that as each one of the water pockets or buckets of the paddle wheel is brought into communication with the tangential water passage 4 of the head, the live water entering the pocket will act upon the blades to give the paddle wheel an impulse in a forward direction. As soon, however, as the water pocket or bucket has been rotated out of communication with the tangential water passage 4 of the head, the water which previously entered the same will become dead, and will flow through the outlet openings 16 of the brush plate into the spaces at the base of the bristles 11. The manner of inclining the blades 9^b of the paddle wheel and the arrangement of the outlet openings 16 adjacent the edges of the blades 9^b at the rear sides of the water pockets tend to forcibly expel the dead water through the openings 16, so that the brush is both rotated and provided with a continuous supply of fresh water when in use.

Having thus described the invention, what I claim as new and desire to secure by Letters Patent, is:—

1. A revolving bath brush, including a head formed with a cylindrical chamber

which is open at one end thereof and has a water passage which enters the chamber tangentially, a pivot post projecting centrally into the chamber from the base thereof, a paddle wheel formed with a hub mounted upon the pivot post and with radially projecting blades arranged to clear the sides and bottom of the cylindrical chamber, a brush plate rigidly secured to the outer face of the paddle wheel and closing the open end of the cylindrical chamber, said brush plate having outlet openings therein, and tufts carried by and projecting from the brush plate.

2. A revolving bath brush including a head formed with a cylindrical chamber which is open at one end thereof and is provided with a water passage which enters the chamber tangentially, a paddle wheel rotatably mounted within the cylindrical chamber and formed with a hub and radially projecting blades arranged to clear the sides and bottom of the chamber and be acted upon by water from the tangential passage, a brush plate closing the open end of the cylindrical chamber and rigidly secured to the paddle wheel, the blades of the paddle wheel being inclined to the plane of the brush plate so that the rear edges of the blades are in advance of the forward edges thereof as the paddle wheel rotates, and the brush plate being provided with a radial series of water outlet openings arranged just in advance of the forward edge of each of the blades of the paddle wheel so that dead water from the pockets between the paddle wheel blades will be forced through the outlet openings of the brush plate as the paddle wheel rotates.

In testimony whereof I affix my signature in the presence of two witnesses.

HOWARD R. WESLEY.
